US00D937815S

(12) **United States Design Patent** (10) **Patent No.:** **US D937,815 S**
(45) **Date of Patent:** **** Dec. 7, 2021**

(54) **ELECTRONIC DEVICE**

(71) Applicant: **GOOGLE LLC**, Mountain View, CA (US)

(72) Inventors: **Maj Isabelle Olsson**, Mountain View, CA (US); **Thao Dang**, Mountain View, CA (US); **Livius Dumitru Chebeleu**, Mountain View, CA (US); **Katherine Morgenroth**, Mountain View, CA (US); **Willy Carteau**, Mountain View, CA (US)

(73) Assignee: **GOOGLE LLC**, Mountain View, CA (US)

(**) Term: **15 Years**

(21) Appl. No.: **29/706,536**

(22) Filed: **Sep. 20, 2019**

(51) **LOC (13) Cl.** **14-03**

(52) **U.S. Cl.**

USPC **D14/242**

(58) **Field of Classification Search**

(57) **CLAIM**

The ornamental design for an electronic device, as shown and described.

DESCRIPTION

FIG. 1 is a top perspective view of an electronic device showing our new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a bottom perspective view thereof.

The broken lines immediately adjacent the shaded areas represent the bounds of the claimed design while all other broken lines are directed to unclaimed portions and are for illustrative purposes only; the broken lines form no part of the claimed design.

1 Claim, 5 Drawing Sheets
